UNITED STATES PATENT OFFICE.

RAY L. STOKELY, OF FLORAL PARK, NEW YORK, ASSIGNOR TO WESTERN ELECTRIC CO., INCORPORATED, OF NEW YORK, N. Y., A CORPORATION OF NEW YORK.

MACHINE-SWITCHING TELEPHONE-EXCHANGE SYSTEM.

Application filed September 25, 1920. Serial No. 412,795.

This invention relates to telephone exchange systems employing machine switching equipment and its object is to provide an improved circuit arrangement to take care 5 of toll calls in such systems, some or all of the substations whereof are equipped with coin boxes.

In accordance with one feature of the invention the toll operator after having built 10 up a connection to the substation selects the connecting circuit used by means of an automatic switch. This switch is accessible to the toll operator over two paths, the path chosen determining the character of operating current to be applied to the line to actuate the coin disposal magnet in the coin box, which current is automatically applied as soon as the connecting circuit is selected. More specifically, a circuit leading to an automatic switch is equipped with two jacks, one having a source of positive current associated therewith for connection to said circuit and the other a source of negative current. After the operator has built up the toll connection, she inserts the plug in the positive or collect jack, and by means of her dial sets the automatic switch to select the connecting circuit over which she has built up the connection. A circuit change thereupon takes place to connect the collect current to such circuit and thence to the selected telephone line to operate the magnet in the coin box to collect the coins deposited by the subscriber. If the coins are to be refunded, the operator inserts the plug into the refund jack and likewise sets the automatic switch on multiples of the used trunk. Upon the completion of the selecting operation in this case, a circuit change takes place 40 to connect the refund current to the connecting circuit and thence to the line to operate the coin box magnet to refund the coins.

Preferably, the selection of the proper current is controlled by a double wound relay which normally prepares a circuit from the refund source to the brushes of the operator's automatic switch, but when the plug is inserted in the collect jack an energizing circuit for the relay is closed to shift the connections to the collect source.

Referring to the drawings, Fig. 1 shows a toll cord circuit, Fig. 2 shows a trunk circuit outgoing from the toll board to a full mechanical office, Fig. 3 shows a selector cir-

cuit, Fig. 3^A shows a fragmentary modification of Fig. 3, Fig. 4 shows the relay and repeating coil equipment associated with the toll transmission selector circuit, Fig. 5 shows the toll transmission selector circuit, 60 Fig. 6 shows a combination toll and local connector circuit, Fig. 7 shows the combination toll and local connector circuit for party line working, Fig. 8 shows a connector circuit for P. B. X. working, Fig. 9, shows a so-called toll terminal loop connector circuit, Fig. 10, shows the trunk circuit with connector for coin collect or refund, Fig. 11 is a diagram of the manner in which the drawings should be placed together in 70 order to read the circuit.

Referring first to Fig. 1, this drawing shows a cord circuit at the toll operator's position. The left hand side of this circuit will be called the toll end and the right hand will be called the toll and trunk end. The operator answers an incoming call by inserting the plug T of the toll end in the answering jack J in the ordinary manner. If the called subscriber is located in a nearby exchange, the call is completed by inserting the plug TT of the trunk and toll end in a toll switching trunk jack TSJ. The operator then actuates the dialing and monitoring key DK which causes the relay B-34 to operate, which in operating energizes a monitoring relay (not shown) to place the operator's telephone set in a monitoring position on the cord. The operator now turns the dial D for the first digit of the wanted number. The dial in moving out of its normal position short circuits the relay B-34 permitting the relay E-72 to operate. Relay E-72 in operating locks itself to battery and transfers the tip of the plug TT through the impulse springs of the dial to the battery. The dial, in returning to normal, interrupts the battery connected to the tip of the plug causing the impulse relay of the trunk circuit of Fig. 2 to operate intermittently, the number of times depending upon the digit involved. This impulse relay, in thus operating, causes the setting of the selector circuit of Fig. 3, which thereupon automatically picks out an idle trunk in the selected level. When the operator has operated the dial for all the digits involved which causes the last switch to be set on the desired line, she restores the monitoring DK. If the called line is not busy, the trunk and 100

105

105

105

110

toll supervisory lamp 100 lights, as a ringing signal, whereupon the operator by depressing ringing key RK causes the connector to start the ringing of the called line, which 5 ringing continues until the called party answers, whereupon the lamp 100 is extinguished. When the called subscriber replaces his receiver, this lamp again lights. If the called line is busy or if one of the 10 selectors had failed to find an idle trunk, the lamp 100 will flash, the frequency of the flashes depending upon the busy condition encountered. The toll operator in response to the flashing of the lamp removes the plug 15 TT of the trunk and toll end of the cord from the toll switching jack TSJ, but before removing the toll plug T the operator by means of her ringing key R'K', rings on the toll line terminating at the jack J to notify 20 the distant operator that the line is free. If the distant operator rings first, however, the toll supervisory lamp 101 lights and is extinguished by operating listening key LK or pulling out the plug T. If the 25 called subscriber is a distant one reached over a toll line, the toll operator inserts the plug TT of the trunk and toll end in the proper jack and by means of her ringing key RK applies alternating current to the 30 trunk to signal the distant operator. When the operator at the distant end applies ringing current to the trunk, the toll supervisory lamp 101 lights until the listening key LK is operated or the connection is taken down. 35 The keys K and K' serve, when operated, to disconnect either end of the cord from the operator's telephone set when the operator is talking on the other. When the plug T of the toll end is inserted in a toll answering 40 jack, relay E-156 operates, in turn operating relay B-162. Relay B-162 opens the circuit of relay E-162 preventing the toll supervisory lamp 101 from lighting. When the plug TT of the trunk and toll end 45 is inserted in toll switching trunk jack TSJ, relay E-99 operates in series with relay E-155 and the lower winding of relay E-156. Relay E-99 disconnects the busy test equipment of the operator's telephone 50 set from the tip of the cord and connects the tip of the cord through to the ringing key. Relay E-155 is marginal and does not operate at this time on account of the high resistance in the sleeve of the trunk 55 circuit. Ringing current applied by the distant operator over the toll line operates the relay A-196 which releases relay B-162. The latter relay in releasing lights the toll supervisory lamp 101 and operates relay 60 E-162 in parallel with the lamp. Relay E-162 locks up under the control of the listening key LK and relay E-156 so that the lamp remains lighted after the ringing ceases and the relay B-162 is re-operated 65 through the back contact of relay A-196.

The lamp 101 may be extinguished by operating the listening key which releases relay E-162 or by taking down the connection which releases relays E-156 and E-162. Relay E-162 is made slow in operating to 70 guard against the possibility of lamp 101 being lighted by Morse impulses. Relay A-196 may be operated for a short time by Morse impulses but will not remain operated long enough to cause the operation 75 of relay E-162. In case relay B-162 should release momentarily, the slow operating feature of the relay E-162 will give the former time to re-operate before the relay E-162 operates and locks. When 80 both ends of the cord are inserted in the toll line jacks the marginal relay E-155 disconnects the relay B-43 from the cord circuit. When ringing current is received from either of the distant offices, relay 85 A-196 operates and lights the lamp 101. If, on a through toll connection of this character, the splitting key K' is operated to disconnect the trunk and toll end from the operator's telephone set, relay B-43 is 90 bridged across the trunk and toll end so that it will operate when ringing current is received from the distant office and flash the lamp 100. When the splitting key K' is in its normal position the circuit for relay 95 B-43 is opened.

Referring now to Fig. 2 which represents a toll switching trunk over which a connection is extended to a nearby exchange, relay C-2 operates over its right hand winding 100 when the operator inserts the plug TT into jack TSJ and by attracting its armature closes a loop circuit leading to the impulse relay A-3, Fig. 3, of the first selector, which in operating energizes slow relay B-3 to 105 prepare the impulse circuit. When the dialing key DK is thrown and the dial is operated, relay A-2 operates connecting relay I-2 across the loop leading to the impulse relay A-3, Fig. 3. Relay I-2 in operating 110 causes relay D-2 to operate, which relay shunts the left hand winding of relay C-2 whereupon the latter relay releases, a circuit through its right hand winding being opened when relay E-72, Fig. 1, operates as 115 the dial is moved out of its normal position. Relay D-2 in operating operates relay E-2 which locks up to the ground at the inner left contact of relay B-2, now energized. Relay E-2 at its outer left contact holds up 120 relay D-2, independently of its original energizing circuit, at the front contact of relay I-2. The dial in restoring intermittently operates relays A-2 and I-2, relay I-2 alternately opening and closing a shunt 125 path around relay D-2. If, during the operation of building up a connection, one of the selectors fails to find an idle trunk in the selected group, it opens the loop circuit including relay I-2. Relay I-2 in closing 130

its back contact, shunts out relay D-2. Relay D-2 in closing its right hand back contact operates relay H-2. Relay H-2 locks up and connects interrupted battery of 60 impulses per minute to the winding of relay C-2 in shunt of the supervisory relay B-43 in the cord circuit, Fig. 1. Relay B-43 follows these impulses and flashes the supervisory lamp 100 to indicate to the operator the failure to find an idle trunk. In case the called line is idle, this condition causes the polarized relay F-2 to operate when the operator restores the key DK which, in operating energizes relay G-2 which cuts the trunk through, thus disconnecting the relay C-2 and A-2 from the circuit leading back to the toll operator's position. In case the called line is busy, however, this polarized relay does not operate, the relays A-2, I-2 and D-2 remain energized. Consequently, the relay H-2 is not operated and at its inner back contact connects interrupted battery of 120 impulses per minute to the winding of relay C-2 which causes the supervisory lamp 100 to flash to indicate to the operator the busy condition of the selected line.

Referring now to Fig. 10. When the operator has built up the connection and found the line idle, applied ringing current, and the subscriber who originated the call and against whom the call was originally charged has responded, she requests the subscriber to deposit the required coins in the coin box, which is preferably of the type shown in Patent No. 1,043,219 of Nov. 5, 1912, to O. F. Forsberg. The coins, in dropping in the coin box, strike bells which, in the well known manner, inform the operator of the character of the deposited coins. The operator then picks up a plug P-10 and inserts it in a collect jack J-10 at her position, and by means of the dial D-10 and an automatic switch shown in Fig. 10, selects the trunk shown in Fig. 3 which is multipled to this automatic switch. If the plug is inserted into the collect jack a relay H-10 operates to prepare a circuit from a source of current of 110 volts positive polarity to the selected line to operate the polarized magnet in the coin box to collect the coins. If, on the other hand, the plug P-10 is inserted in the refund jack R-10, relay H-10 is not operated and consequently negative current of 110 volts is impressed upon the called line to operate the polarized magnet in the coin box in the opposite direction to refund the coins. The upper armature of the relay H-10 in its attracted position closes a circuit from a tone source of one character to the operator's head set which informs her that positive impulses of current are being transmitted to the called line. This relay in its attracted position gives a different tone to the operator's head set to indicate to her

that negative impulses are being transmitted to the called line. The operator is thus informed whether the coin collect circuits are functioning properly or not. As shown in the said Forsberg patent, when the polarized relay operates in either direction it disconnects itself from ground, whereupon the relay J'-10 in the coin current circuit ceases to operate to transmit this tone thus informing the operator that the polarized magnet has functioned. She thereupon withdraws the plug P-10 from the jack whereupon the automatic switch of Fig. 10 is restored to its normal position.

Having described in a general manner the operation of the system, a call will now be traced in detail.

The toll operator, having been informed of the number of the wanted line and assuming this line to be in a nearby exchange, tests for an idle trunk by touching the tip of her plug TT to the sleeve of the jack TSJ of the toll switching trunk in the well known manner, and if she does not receive a click in her receiver she inserts the plug TT into the toll switching trunk jack TSJ. A circuit is thereupon closed to operate relays E-99, (Fig. 1) and B-2 (Fig. 2). Relay E-99 in operating disconnects the operator's busy test circuit from the tip of the cord. Relay B-2 (Fig. 2) in operating prepares certain circuits which will be traced later. This trunk will now test busy at the other operator's positions due to battery applied to the sleeve multiples by the sleeve of the plug TT. The insertion of the plug also closes the following circuit to energize relay C-2: free pole of battery, resistance 200, right hand winding of relay C-2, conductor 201, armature 202 of relay G-2, conductor 203, ring of the jack TSJ and plug TT, conductor 110, lower normal contact of ringing key RK, right hand winding of retardation coil 111, relay B-43, armature and back contact of relay E-155 which is not operated when the plug TT is inserted in the toll trunk switching jack, but only when it is inserted in a toll line leading to a distant office, left hand winding of retardation coil 111, upper normal contact of ringing key RK, armature and front contact of relay E-99, conductor 102, right hand normal contact of relay E-72, conductor 103, tip of the plug TT, tip of the jack TSJ, armature 204, back contact of relay G-2, and relay A-2 to ground. Relay A-2 is marginal and does not operate in this circuit. Relay C-2 in attracting its armature closes the following circuit to operate relay A-3, Fig. 3, which is the impulse relay of the first selector, which is shown in Fig. 3: free pole of battery, lower winding of relay A-3 (Fig. 3), conductor 300, back contact and armature 301 of relay D-3, conductor 302, conductor 205, conductor 206, outer left hand armature

and back contact of relay H—2, conductor 207, armature and front contact of relay C—2, left hand winding of relay C—2, conductors 208 and 209, inner right armature and front contact of relay B—2, conductor 210, polarized relay F—2, conductor 211, conductor 212, conductor 303, armature 304, back contact of relay D—3, conductor 305, upper winding of relay A—3, conductor 306, normally closed contact of switch 307, operated on the eleventh rotary step of the selector, to ground. The operator now throws the dialing and monitoring key DK, whereupon a circuit is closed to operate relay B—34, Fig. 1, which in attracting its armatures causes the operator's head set to be connected across the cord. She now rotates the dial D for the first digit of the wanted number. The closure of the contact 104 of the dial as the dial moves off normal, shunts the relay B—34 which operates the relay E—72 and releases relay B—34. Relay E—72 in attracting its left hand armature locks itself to ground at the contact of the dialing key DK which when actuated remains in its operated position until manually released by the operator. Relay E—72 in closing its right hand contact connects the free pole of battery through the impulse contact 108 of the dial to the tip of the plug interposing a break in the tip conductor. The interposition of this break in the tip conductor opens the circuit heretofore traced through the right hand winding of relay C—2. Marginal relay A—2 now operates in series with the impulse contact of the dial, the circuit being as follows: free pole of battery, resistance 109, impulse contact 108, right hand armature and front contact of relay E—72, conductor 103, tip of the plug TT, tip of the jack TSJ, armature 204 and back contact of relay G—2, conductor 213 and relay A—2 to ground. Relay A—2 in attracting its left hand armature bridges relay I—2 across the tip and ring of the cord in parallel with the left hand winding of relay C—2. Relay I—2 in attracting its armature closes a circuit, to operate relay D—2 as follows: free pole of battery, resistance 214 conductor 215, relay D—2, conductor 216, right armature and front contact of relay I—2 conductor 217, contact 218 of relay G—2 to ground. Relay D—2 in attracting its left armature short circuits the left hand winding of relay C—2 which thereupon releases, thus opening one of the bridges to the impulse relay A—3 and leaving bridged across the circuit only relay I—2. This circuit may be traced as follows: free pole of battery, lower winding of relay A—3, conductor 300, armature 301 and back contact of relay D—3, conductor 302, conductors 205 and 206, outer left hand armature and back contact of relay H—2, conductor 207, conductor 298, relay I—2, left

hand armature and front contact of relay A—2, conductor 211, conductor 212, conductor 303, armature 304 and back contact of relay D—3, conductor 305 upper winding of relay A—3 and upper normal contacts 307 to ground. Relay D—2 at its right armature and front contact closes the following circuit to operate relay E—2: free pole of battery, relay E—2 conductor 220, right armature and front contact of relay D—2, conductor 221, conductors 222 and 228, inner left armature and front contact of relay B—2 to ground. Relay E—2 in attracting its inner right armature locks itself to grounded conductor 222. The functions of this relay will be later described. Dial D, Fig. 1, in returning to normal, interrupts at its impulse contact 108 the circuit of the impulse relay A—2, Fig. 2, which at its left armature interrupts the circuit of the impulse relay A—3, Fig. 3, the number of times corresponding to the first digit of the wanted number. Upon each retraction of the armature of relay A—3, the following circuit is closed for the vertical magnet 310 of the first selector: grounded armature 311, and back contact of relay D—3, conductor 312, armature and back contact of relay A—3, lower armature and front contact of relay B—3, slow relay C—3, vertical magnet 310, and free pole of battery. On the first step of the selector off normal springs 313 close the following circuit for relay 314: free pole of battery, relay 314, conductor 315, off normal springs 313, conductors 316, 317, armature and front contact of relay C—3 to ground at the armature and front contact of relay B—3. Relay 314 in attracting its upper armature locks itself over the following circuit: free pole of battery, relay 314, conductor 315, off normal contact 313, conductor 316, armature and back contact of rotary magnet 318, conductor 319, conductor 320, upper armature and front contact of relay 314, conductor 321 to ground at the armature 311 and back contact of relay D—3. Upon the cessation of the impulses, however, relay A—3 remains energized and consequently relay C—3 which is slow to release, after an interval, releases whereupon the following circuit is closed to energize the rotary magnet 318 of the selector to step the selector brushes on to the first trunk in the selected level: free pole of battery, magnet 318, conductor 322, lower armature and front contact of relay 314, upper normal contact of relay C—3, upper armature and front contact of relay B—3 to ground. At the end of its stroke, the rotary magnet 318 opens the locking circuit traced for relay 314. Relay 314 in retracting its lower armature opens the circuit of the rotary magnet. If the first trunk is busy, ground is present on the test multiple 323 thereof, whereby the following circuit is closed to energize relay 314: 130

grounded multiple 323, test brush 324, conductor 325, armature 326 and back contact of relay D-3, conductors 327, 319, back contact and armature of magnet 318, conductor 316, contact 313, conductor 315, relay 314 to free pole of battery. Relay 314 in attracting its upper armature again locks itself through the back contact of the rotary magnet and in attracting its lower armature 5 again closes the circuit of the rotary magnet whereupon the selector brushes are stepped to the next trunk. This action of the relay 314 and rotary magnet is continued until an idle trunk is found which is indicated by the absence of ground on the test multiple 323 thereof. When the rotary magnet at the end of its stroke positions the brushes on to an idle trunk and no ground is present, relay 314 does not energize but relay D-3 energizes over the following circuit: free pole of battery, relay 314, conductor 315, contact 313, conductor 316, armature and back contact of rotary magnet 318, conductor 319, conductor 327, 20 conductor 328, relay D-3, conductor 329, lower normal contact of switch 307, conductor 330, to ground at the upper armature and front contact of relay B-3. Relay 314 is marginal and does not operate in this 25 circuit. Relay D-3 in attracting its armatures 304 and 301 extends the talking conductors through to the selector brushes and cuts off impulse relay A-3.

Assuming now that the selector has failed 30 to find an idle trunk. In that event on the eleventh rotary step, switch 307 operates and opens at its uppermost contacts, the circuit of the impulse relay A-3 which causes the selector (Fig. 3) to restore.

The opening of this loop circuit also causes relay I-2 to be permanently deenergized. Relay A-2 in remaining attracted and the relay I-2 being inert, the following short circuit is closed about the slow relay 45 D-2 to cause the same to release: free pole of battery, resistance 214, right hand armature and front contact of relay A-2, armature and back contact of relay I-2, conductor 217, contact 218, to ground. It will be understood that relay D-2 is slow 50 to release as shown and holds up between the impulses of one digit. Relay D-2 in retracting its right armature operates relay H-2 over the following circuit: free pole of 55 battery, relay H-2, conductor 222, armature and back contact of relay D-2, conductor 220, inner right hand armature and front contact of relay E-2 to ground on conductor 242. Relay H-2 in attracting its 60 inner left armature locks itself up to grounded conductor 242 and in attracting its inner right armature connects interrupter 223 to the inner left hand armature and front contact of relay E-2 to shunt the 65 resistance 200 to cause supervisory relay B-43 in the cord circuit to flash the trunk and toll supervisory lamp 100 at the rate of 60 flashes per minute when the operator restores the key DK. This rate of flashing will indicate to the operator that one of the 70 switches has encountered a busy trunk group whereupon she will pull out the plug and will then wait and set up the connection later, or insert the plug into another jack and again set up the connection by way of 75 another trunk. While the interrupting machine 223 is connected to the front contact of relay H-2 as soon as relay D-2 releases, this operation is not effective to flash the lamp until the operator, after having turned 80 the dial for the last time, releases her dialing key DK, Fig. 1. The opening of the lowermost contact of this key releases relay E-72 which in retracting its right armature again closes the loop circuit including the right 85 hand winding of relay C-2, Fig. 2, and the relay A-2, Fig. 2 and B-43 (Fig. 1). It will, of course, be understood if no idle trunk is found relay G-2 is not energized. The relay H-2 in attracting its outer left 90 armature interposes a break in the loop circuit leading to the selector (Fig. 3) thus presenting the subsequent sets of impulses from operating the switches.

The seizure of the toll transmission selector, Fig. 5, with which the relay and repeating coil equipment of Fig. 4 is associated, causes the closure of the following circuit for impulse relay A-5, Fig. 5 of the toll transmission selector: free pole of battery, 95 right hand winding of relay A-5, conductor 500, conductor 400, conductor 401, outer left armature and back contact of relay B-4, conductor 402, contact 403 of relay F-4, conductors 404, 405, upper left hand 100 winding of repeating coil 406, conductor 407, multiple terminal 351, brush 350, conductor 352, armature 304 and front contact of relay D-3, conductors 303, 212, conductor 211, left armature and front contact of relay 105 A-2, relay I-2, conductors 298, 207, outer left hand armature and back contact of relay H-2, conductors 206, 205, 302, armature 301 and front contact of relay D-3, conductor 332, brush 333, multiple terminal 334, conductor 408, lower left hand winding of 110 repeating coil 406, conductor 409, contact 410 of relay F-4, conductor 411, contact 412 of relay B-4, conductor 413, conductor 501, through the left winding of relay A-5 115 to ground at the lower normal contact of the switch 502 which is operated on the eleventh rotary step of the transmission selector. The impulse relay A-5 in attracting its right armature energizes slow relay B-5. 120 This relay in attracting its left armature closes a circuit for relay 336 which in attracting its armatures applies a local ground to the test multiple 323 to cause this trunk to test busy. Relay 336 is provided when the 125 130

transmission selector is not located in the same office as the selector circuit of Fig. 3, to take care of differences in ground potentials and trunk resistances. If the toll selector 5 is in the same office, ground from the outer left armature and front contact of relay B-5 is transmitted to the test multiple 323, and relay 336 is omitted. As indicated in the drawing Fig. 3^A. When the relay B-5 10 operates it closes at its right hand armature the following circuit for relay D-4 in the relay and repeating coil circuit, Fig. 4: ground, right armature and front contact of relay B-5, conductors 503 and 518, conductor 504, conductor 505, contact 506 of relay D-5, conductors 507, 414, outer right hand armature and back contact of relay F-4, conductor 415, relay D-4 to free pole battery. 15

20 The second operation of the dial by the operator transmits the second digit of the called line causing relay A-2 Fig. 2 to open and close the loop circuit for the relay A-5, which in vibrating its right hand armature transmits impulses over the following circuit to the vertical magnet 508 of the toll transmission selector: right armature and back contact of relay A-5, inner armature and front contact of relay B-5, conductor 509, armature 510 and back contact of relay D-5, conductor 511, slow relay C-5, magnet 508 to free pole of battery. The brushes of the toll transmission selector are thus elevated to the desired 25 level. When the dial returns to normal and maintains the relay A-2 energized, relay A-5 remains energized and, after a slight interval, slow relay C-5 releases. When the relay C-5 operated on the first impulse 30 and the selector took its first step, relay E-5 corresponding to relay 314, Fig. 3, operated over the following circuit: free pole of battery, relay E-5, upper contact of off normal switch 515, conductor 516, armature 35 and front contact of relay C-5, conductor 517, conductor 518, conductor 503 to ground at the right armature and front contact of relay B-5. In attracting its inner armature, relay E-5 locks itself to the upper 40 armature and back contact of slow relay F-5, this circuit including the armature and back contact of rotary magnet 519. These circuits are similar to those of the selector of Fig. 3. Upon the cessation of 45 the impulses and the release of the slow relay C-5, the circuit of the rotary magnet is closed as follows: free pole of battery, magnet 519, outer armature and front contact of relay E-5, normal contact of relay C-5, conductor 517, conductor 518, conductor 503, right armature and front contact of slow relay B-5 to ground. The rotary magnet advances the brushes on to the terminals of the first trunk and at the end of 50 its stroke opens the locking circuit of the 55 relay E-5 which releases opening the circuit of the rotary magnet. If the trunk is busy, relay E-5 again energizes over the following circuit: free pole of battery, relay E-5, upper contact of switch 515, conductor 516, conductor 520, armature and back contact of rotary magnet 519, conductor 521, conductor 522, back contact and armature 523 of relay D-5, conductor 524, lowermost armature and back contact of relay F-5, conductor 525, test brush 526 to ground on the test multiple 527. Relay E-5, in attracting its inner armature again locks up through the upper armature and back contact of relay F-5 and at the other 60 armature again closes the circuit of the rotary magnet which advances the brushes to the next trunk and at the end of its stroke opens the locking circuit of relay E-5 which in retracting its armature opens the 65 circuit of the rotary magnet 519. The switch 502 of the toll transmission selector, Fig. 5, corresponds to the switch 307 of the selector circuit, Fig. 3. Its function is to open the circuit of the impulse relay A-5 70 on the eleventh rotary step of the toll transmission selector, that is to say, if all the trunks in the group are busy. The opening of this circuit releases the switch and causes relay I-2, Fig. 2, to become permanently 75 inert which causes the release of slow relay D-2 and prepares a circuit for the interrupter 223 which results in the flashing of the trunk and toll supervisory lamp 80 when the operator restores her dialing key 85 as described in detail in connection with Fig. 3. If, however, an idle trunk is found, relay D-5, which corresponds to relay D-3, Fig. 3, operates over the following 90 circuit: free pole of battery, relay E-5, upper contact of switch 515, conductor 516, conductor 520, armature and back contact of magnet 519, conductors 521, 522, relay D-5, upper normal contact of switch 502, conductors 530, 503 to ground at the right 95 armature and front contact of relay 502. Relay E-5 is marginal and does not operate in this circuit in series with the relay D-5. Relay D-5 then operates and in attracting its armatures 531 and 532 extends 100 the talking conductors through to the talking brushes 533 and 534. The attraction of the armature 523 of relay D-5 grounds the test brush 526 and consequently test multiple 527 of the selected trunk, causing the 105 same to test busy to other selectors. The contact 535 is made before the contact 506 is broken by the armature 537 of the relay D-5. Consequently relay D-4, Fig. 4, in 110 the relay and repeating coil equipment is maintained energized over the following 115 circuit: free pole of battery, relay D-4, conductor 415, outer right armature and back contact of relay F-4, conductor 414, conductor 507, contact 535, conductor 538, 120

125

130

brush 539, multiple 540, control conductor 541, conductor 600, conductor 601, armature 602 and back contact of relay K-6, conductor 603, sleeve conductor 650, conductor 542, 5 multiple 527, brush 526, conductor 525, lowermost armature and back contact of relay F-5, conductor 524, armature 523 and front contact of relay D-5, conductor 518, conductor 503, to ground at the right armature and front contact of slow relay B-5. Thus, the circuit for relay D-4 (Fig. 4) is maintained closed as the circuit is extended from switch to switch. As will hereafter appear, relay F-4 is not operated until 10 the desired line is found idle and seized when it reverses the direction of current flow in the circuit leading back to the toll operator's position to light the supervisory lamp 100 to indicate to her the idle condition of the line, whereupon she will cause the connector to begin the automatic ringing operation. The switch of Fig. 6 to which the connection has been extended is a combination toll and local connector containing 15 multiples of ordinary lines in its bank. This switch is accessible not only to the toll transmission selectors of Fig. 5, but also to the local selectors which are used by the subscribers in building up their own local connections. The seizure of the connector causes the closing of the following circuit for the impulse relay A-6; free pole of battery, upper winding of relay A-6, conductor 604, conductor 605, left winding of slow 20 relay J-6, conductors 606 and 607, lowermost armature and back contact of relay K-6, ring conductor 646, conductor 543, multiple 544, brush 534, conductor 545, armature 532 and front contact of relay D-5, left armature and front contact of relay 25 A-5, ring conductor 546, conductor 416, armature 417 and back contact of relay K-4, conductor 419, lowermost armature and contact of relay H-4, conductor 421, lower right hand winding of the repeating coil 30 406, resistance 460, conductor 422, left armature and front contact of relay D-4, resistance 423, conductor 424, resistance 461, upper right hand winding of repeating coil 35 406, upper armature and back contact of relay H-4, conductor 425, uppermost armature and back contact of relay K-4, tip conductor 426, conductor 547, armature 531, and front contact of relay D-5, conductor 548, brush 533, multiple 549, tip conductor 550, conductor 610, upper armature and back contact of relay K-6, conductor 611, conductor 612, lower winding of relay A-6 to ground. Relays J-6 and A-6 operate 40 in this circuit, the former at its innermost right armature closing a locking circuit for itself as follows: free pole of battery, right winding and right innermost armature and front contact of J-6, conductor 614, conductor 631, conductor 615 to ground at the 45 armature 616, and front contact of slow relay B-6 which is energized upon the energization of the impulse relay A-6. Relay B-6 grounds the sleeve wire 617, leading to the test multiples in the local selectors, this 50 circuit leading from grounded armature 616, conductor 615, to conductor 617. The return of the dial to normal after the operation of transmitting the tens digit of the wanted number interrupts the circuit of relay A-2, Fig. 2, which in turn interrupts the circuit of the impulse relay A-5, Fig. 5, which in vibrating its armatures causes the impulse relay A-6 of the connector to transmit impulses to the vertical magnet 55 618 of the connector over the following circuit: free pole of battery, magnet 618, slow relay 619, right contact of off normal switch 620, conductor 621, lower armature and front contact of relay B-6 to ground at the 60 armature and back contact of the impulse relay A-6. At the first step of the connector, the off normal springs 620 are shifted and the succeeding impulses are transmitted by way of the upper armature and front contact of relay 619 and the contact 622 now closed at the off normal springs 620. The selector brushes are thus lifted to the desired level and upon the cessation of the impulses, impulse relay A-6 remains 65 energized and relay 619 in series with the vertical magnet releases preparing the circuit of the rotary magnet 623. The units impulses pass through the back contact of the impulse relay A-6, lower armature and front contact of relay B-6, conductor 621, off normal contact 622, back contact of slow relay 619, conductor 624, left armature and back contact of relay G-6, conductor 625, uppermost armature and back contact of relay H-6, rotary magnet 623 to free pole 70 of battery. The connector is thus stepped around into engagement with the desired line. 75 If this line is idle, potential is present on its test multiple 626 through the cut off winding of the line switch and, the following circuit is closed to operate relay H-6: multiple 626, brush 627, conductor 628, right-hand armature and back contact of relay E-6, connector 629, upper winding of relay H-6, conductor 630, right hand armature and back contact of relay G-6, conductor 631, conductor 615, armature 616 of relay B-6 to ground. Relay H-6 in attracting its armature 632 locks itself to the grounded sleeve wire 650 and extends this grounded conductor over conductor 633, middle right armature and front contact of relay J-6 conductor 634 to the relay K-6. Relay K-6 in attracting its armature 602 disconnects the grounded sleeve wire 650 from the control lead 600 leading back to the relay D-4, Fig. 4, of the relay and repeating coil equipment cir- 80 85 90 95 100 105 110 115 120 125 130

cuit. Relay D-4 in retracting its outer right hand armature operates relay F-4, Fig. 4, over the following circuit: free pole of battery, relay F-4, conductor 428, outer right armature and back contact of relay D-4, conductor 429, conductor 550, armature 523 and front contact of relay D-5, conductor 518 to ground at the right armature and front contact of relay B-5. Relay F-4 in attracting its outer right armature closes a substitute ground to hold up the relay F-6 to prevent ringing from occurring at this time: ground right hand armature of relay E-4, conductor 430, right armature and back contact of relay B-4, outer right armature and front contact of relay F-4, control conductors 414 and 507, contact 535 of relay D-5, conductor 538, brush 539, multiple 540, conductor 541, conductor 600, front contact, armature 635 and lower winding of relay F-6 to free pole of battery. Relay F-6 was energized upon the first impulse to the vertical magnet, this circuit being as follows: free pole of battery, lower winding of relay F-6, lower armature and front contact of slow relay 619, innermost right hand armature and front contact of relay J-6, conductor 614, conductors 631 and 615 to ground at the upper inner armature and front contact of relay B-6. When energized, relay F-6 locks by way of its armature 635 and front contact, conductor 601, armature 602 and back contact of relay K-6 to grounded sleeve wire 650. Consequently, the operation of relay K-6 to cause the reversal of direction of the current flow in the loop leading back to the toll operator's position would deenergize relay F-6, and unless a substitute circuit is provided for holding up relay F-6 the ringing operation would automatically take place. This is prevented by applying ground to the control conductor 600 over the circuit traced to hold the relay F-6 until the operator, by depressing a key as will be explained, releases relay F-6 to start the automatic ringing operation. The release of the relay D-4 and the consequent energization of relay F-4 as described reverses the direction of current flow in the talking conductors leading back to the operator's position. After having turned the dial for the last time, the operator restores her dialing key DK which releases relay E-72 which disconnects the dial from the tip of the plug causing the release of the relay A-2, Fig. 2, and causes the closure of an energizing circuit for the right hand winding of relay C-2, relay B-43 and relay A-2. Relay A-2 it will be remembered, releases under this condition and in retracting its left armature deenergizes relay I-2, which in releasing causes the release of relay D-2. The polarized relay F-2 is now bridged across the following circuit: upper talking conductor

212, Fig. 2, conductor 211, polarized relay F-2, conductor 210, inner right armature and front contact of relay B-2, conductor 209, conductor 208, left hand winding of relay C-2, armature and front contact of relay C-2, conductor 207, outer left armature and back contact of relay H-2, conductor 206 to lower talking conductor 205. The reversal of the direction of current in these talking conductors due to the operation of relay F-4 causes the relay F-2 to cooperate closing the following circuit for relay G-2: free pole of battery, relay G-2, conductor 224, contact 225, of relay F-2, conductors 226, 227, 228, inner left armature and front contact of relay B-2 to ground. Relay G-2 locks itself up over the following circuit: free pole of battery, relay G-2, conductor 224, conductor 229, front contact and armature 230, of relay G-2, conductor 231, conductor 227 to ground at the inner left hand armature of relay B-2. Relay G-2 connects the talking conductors of Fig. 2 through to the talking conductors of Fig. 1 whereupon the trunk and toll relay B-43 operates in series with the relay A-5, Fig. 5, and lights the supervisory lamp 100 as a ringing signal to the toll operator. Relay G-2, Fig. 2, cuts off the bridge including relays C-2 and A-2. The operator now operates her ringing key RK which impresses alternating current upon the talking conductors and operates the alternating current relay C-4 which in attracting its armature operates the relay E-4. This relay in attracting its right armature opens the circuit heretofore traced, which has been holding relay F-6, Fig. 6, energized. This relay in retracting its armature 637 connects ringing current to the called line through the upper winding of relay F-6. This ringing current is automatically continued until the called party removes his receiver, resulting in the increase in the current through the upper winding of relay F-6 causing the same to operate removing the ringing current. The attraction of the armature 635 of this relay closes a locking circuit for the same over control conductor 600. The extension of the tip and ring conductors by relay F-6 to the called line operates relay A-4 over the winding of which talking current is fed to the called line. Relay A-4 in operating energizes relay B-4 which in attracting its right hand armature applies ground to the conductor 414 to hold up relay F-6, Fig. 6, independently of the relay E-4. Relay B-4 in attracting its left hand armature opens the connection of battery through the windings of relay A-5, Fig. 5, to the talking conductors 407, 408, leading back to the operator's position which causes the deenergization of supervisory relay B-43. This relay in retracting its armature extinguishes the supervisory lamp 130

100 which notifies the operator that the subscriber has responded. Talking current is fed to the called line over the winding of relay A-4 and the repeating coil 406. This 5 talking circuit is a standard repeating coil transmission circuit used in long distance connections. Talking current is fed to the calling line from the calling distant exchange. During conversation the trunk 10 leading from the left hand windings of repeating coil 406 through the right hand winding of the repeating coil (not shown) at the distant office is dry, in accordance with standard practice. The operator may now 15 request the subscriber at the substation shown in Fig. 6 to deposit the necessary coins in the coin box which may be of the type shown in said Patent 1,043,219. These coins in passing through the box strike 20 gongs whereby the operator is informed of the denominations of the coins inserted. When she is satisfied that the proper coins have been deposited she picks up her plug P-10, Fig. 10, and after touching the tip of 25 the plug to the tip of the jack and finding the same idle, she inserts it into the collect jack J-10. The insertion of the plug P-10 closes a circuit for relays E-91 and E-99 over the sleeves of the plug and jack, and relay E-91 thereupon operates the signals 30 1002, and 1003 at the positions in which the multiples of this jack appear. Relay E-99 in operating disconnects the busy test circuit and connects the dial D-10 to the tip 35 of the plug. Battery on the sleeve of the plug causes the multiples of the seized trunk to test busy at the other positions. The operator knowing the number of the trunk shown in Fig. 3 because of the designations 40 on the jacks themselves or the designation strips associated with the jacks, now rotates her dial to set the automatic switch shown in Fig. 10 to connect with the multiples of the used trunk which appear in this switch. 45 The automatic switch of Fig. 10 and all apparatus shown at the right of the dotted line is located at the distant automatic office; that is to say in the same office with the selector of Fig. 3. The equipment shown at 50 the left of the dotted line of Fig. 10 is located at the toll office. The insertion of the plug P-10 energizes the impulse relay A-10 over the following circuit: free pole of battery, resistance 1050, impulse springs 55 of the dial, armature and front contact of relay E-99, tip of the plug P-10, tip of the jack J-10, conductor 1005, conductor 1006, upper normally closed contact of off normal switch 1007, conductor 1008, impulse 60 relay A-10, conductor 1009, conductor 1010, ring of the jack J-10, ring of the plug P-10 to ground. The impulse relay in operating energizes the usual slow to release relay B-10. Relay B-10 in attracting its 65 outer right armature closes a circuit for the upper winding of relay H-10. This winding of relay H-10 when energized is not sufficiently strong to cause the relay to operate but is sufficient to cause relay H-10 to operate when the current through the lower 70 winding is in the right direction to aid the current in the upper winding; lower winding of relay H-10 will not cause the operation of the relay H-10, when the current flowing in the upper winding opposes that 75 flowing in the lower winding. The lower winding however is shunted while the switch shaft is in its normal position.

Upon the return movement of the dial the impulses are transmitted to the impulse relay A-10. Upon each retraction of the armature of this relay an impulse is transmitted over the following circuit to the vertical magnet 1013 of the switch; ground, armature and back contact of relay A-10, inner 80 armature and front contact of relay B-10, lower normally closed contact of off normal switch 1007, slow relay C-10, vertical magnet 1013 to free pole of battery. The first 85 step of the switch operates the off normal switch 1007 which removes the short circuit from around the lower winding of the relay H-10, whereupon relay H-10 operates and shifts the armature 1012 from its normal connection with the refund source of 110 90 volts negative current to connection with the collect source of 110 volts positive current.

Upon the first vertical step the off normal switch 1007 operates and the succeeding impulses then pass by way of contact 1015 and the armature and front contact of slow relay C-10. Upon the cessation of the impulses the slow relay C-10 releases preparing a circuit for the rotary magnet 1016 100 closed upon the return of the dial for the units impulses. The impulses now pass from the back contact to the stepping relay A-10, inner armature and front contact of relay B-10, contact 1015, armature and back of 105 relay C-10, slow relay E-10, outer right hand armature and back contact of relay D-10, rotary magnet 1016 to free pole of battery. Relay E-10 in attracting its outer left armature energizes relay D-10 which 110 in attracting its left armature locks up to the outer right armature of relay B-10. Relay E-10 in attracting its inner left armature operates relay F-10. Relay E-10 115 in attracting its right armature connects the rotary magnet in the stepping circuit independently of the outer right armature of the relay D-10. Now when the units impulses have all been transmitted the slow relay E-10, after a slight interval, releases. The retraction of its inner left armature opens the circuit through the left winding of relay F-10. If at this 120 time the interrupter 1017 is on a metallic segment relay F-10 will be held up by its 125 130

armature. When the interrupter passes to the next insulating segment relay F-10 releases and its armature connects relay G-10 over the inner right armature and front contact of relay D-10 to the interrupting machine 1017. It will be apparent that the relay F-10 is provided to insure that the first impulse to relay G-10 will be a full one. The brushes 1018 and 1019, being now in contact with multiples 1020 and 1021 of the trunk shown in Fig. 3, upon the first engagement of the interrupting machine brushes with the metallic segment after relay F-10 has released, an impulse is transmitted to the relay G-10 which, in attracting its armature connects the source of collect current by way of the brush 1018, multiple 1020, conductor 345, Fig. 3, uppermost armature and front contact of relay D-3, Fig. 3, conductor 337, brush 338, multiple 339, conductor 432, relay G-4, resistance 434 to ground. Relay G-4 connects relay K-4 to the interrupter 1017 which is the same machine as that indicated by the same reference character in Fig. 10. Each time relay K-4 operates, it extends the conductor 432 to the ring conductor 416 and tip conductor and thence to the called line, this circuit including switch hook springs of the substation telephone set, contact 638 in the coin box, polarized magnet P of the coin box to ground. Current will flow through relay J'-10, Fig. 10, to ground at the coin box each time relay G-10 operates until the coins have been collected in case they are not collected upon the first operation of the polarized magnet P. When the polarized magnet P operates and collects the coins the contact 638 in the coin box at the substation is opened consequently relay J-10 no longer operates. Each time relay J'-10 operates tone is placed on the toll switching trunk to indicate to the operator that the proper current is being sent out to the called line. This circuit leads from a source 1022 over the front contact and armature 1023 of the relay H-10, armature and front contact of relay J'-10, condenser 1069, brush 1019, multiple 1021, Figs. 10 and 3, which multiple is connected to the tip conductor of the trunk from whence it is transmitted to the operator's head set. The toll operator, ceasing to hear the tone impulses, knows that the coins have been collected and pulls out the plug P-10. If the polarized magnet fails to collect the coins or if the coin box fails to function properly for some reason or other the contact 638 remains closed and the repeated impulses of tone will inform the operator of this condition and she will pull out the plug and report the line. The removal of the plug causes the release of the impulse relay A-10 and slow relay B-10 which closes the following circuit for the release magnet J-1025; free pole of

battery, magnet J-1025, upper contact of the off normal switch 1007, inner armature and back contact of slow relay B-10 armature and back contact of relay A-10 to ground. The release magnet restores the 70 switch and the switch, upon reaching its normal position, restores off normal switch, 1007.

If the operator had plugged into the refund jack R-10, if for any reason the coins 75 were to be refunded, the current in the lower winding of relay H-10 would oppose that following in the upper winding and relay H-10 would not operate when the off normal switch 1007 opened the shunt about the 80 lower winding. Consequently the armatures of relay H-10 would have remained retracted, the armature 1012 connecting the refund source of negative current to the called line to operate the polarized magnet 85 P in the opposite direction to refund the coins to the subscriber. Armature 1023 at its contact would connect a source of refund tone 1027 in circuit with the operator's head set each time the relay J'-10 operated. As 90 in the case where the coins were collected, the toll operator ceasing to hear refund tone impulses knows that the coins have passed through the box and she removes the plug 95 from the refund jack.

It is of course understood that the tone 100 sources 1022 and 1027 are of different character for example, the refund source can be 460 pulsations per second and the collect source 150 pulsations per second.

Assuming now that the desired line when selected by the connector is busy. In that condition the test multiple 626, Fig. 6, is grounded. When test wiper 627 is set on the busy multiple 626, ground is extended 105 over brush 627, conductor 628, contact 640 of relay E-6, conductor 641, armature 642 and back contact of relay H-6, conductor 643, relay G-6 to free pole of battery. Relay G-6 energizes and when relay E-6 110 releases locks itself up over the following circuit; free pole of battery, relay G-6, conductor 643, armature 642 and back contact of relay H-6, conductor 641, make before break contact of relay E-6 right armature and front contact of relay G-6, conductor 631, conductor 615 to ground at the armature 616 and front contact of relay B-6. Relay G-6 in the case of a local call connects busy tone from the source 645 to the calling line. In the case of a toll call this busy tone is not used, a flashing signal being given to the operator instead. By reason of the ground connection to the multiple 626 of the selected line relay H-6 115 does not operate. Consequently, relay K-6 is not energized to open the circuit of relay D-4 Fig. 4 as described in the case of an idle line. Inasmuch as relay D-4 remains 120 energized, relay F-4, whose circuit is main- 125

tained open at the outer right armature and back contact of relay D-4 is not operated and no current reversal in the trunk leading back to the operator's position occurs. Polarized relay F-2, Fig. 2, is not operated in this case and relay G-2 remains inert. Since the relay E-2 is locked up at this time and relay G-2 is inert, when the operator restores her dialing key DK the following circuit is closed from interrupter 233 of 120 impulses per minute to shunt out resistance 200 to cause the supervisory relay B-43 to flash the lamp 100, 120 times per minute, which indicates to the operator that the selected line is busy, whereupon she pulls out the plug TT from the trunk switching jack TSJ which results in the release of all switches and the normal condition of all the apparatus including the various locked up relays. During the existence of a connection in order to recall the operator, the called subscriber by moving his hook up and down causes the supervisory lamp 100 at the toll operator's position to flash as in manual practice without releasing the switches. This is apparent from the preceding description inasmuch as relay A-4 is in circuit with the called line and each time it attracts its armature operates the relay B-4 which removes battery and ground from the trunk conductors leading back to the supervisory relay B-43 and puts a bridge across the relay A-5 to hold it operated as long as the subscriber has his receiver off the hook. When the called subscriber replaces his receiver he lights the lamp 100 at the toll operator's position, Fig. 1. The operator may re-ring the subscriber if necessary if she desires to recall him by actuating her ringing key RK which in operating operates relay C-4 to operate E-4 which in attracting its right hand armature again releases relay F-6 which initiates the automatic ringing operation. The control of this relay F-6 was removed from the relay E-4 by the attraction of the right armature of relay B-4 when the called subscriber responded and was restored to the relay E-4 and consequently to the operator when the called subscriber replaced the receiver and deenergized relay B-4. When the operator desires to break down the connection after the called subscriber has replaced his receiver, she removes the plug TT from the toll switching jack TSJ. This releases relay A-5, Fig. 5, which causes the restoration of all the switches. If, however, the operator pulls out the plug while the called subscriber still has his receiver off the switch hook, the switches are not released since relay A-5 which controls the release is maintained energized over the following circuit: battery, right hand winding of relay A-5, conductor 500, conductors 400 and 401, resistance 435, inner left armature

and front contact of relay B-4, conductors 413 and 501, left winding of relay A-5 to ground at the lower normal contact of off normal contacts 502, it being noted that the relay B-4 which controls this loop circuit is itself controlled by relay A-4 in circuit with the called line and controlled at the switch hook of said line.

Assuming, however, that the called subscriber has replaced his receiver, when the operator removes the plug, relay A-5 in releasing deenergizes relay B-5. Relay B-5 in retracting its outer left armature removes ground from the sleeve conductor 551 leading over the sleeve conductor 436 to the relay 336 which in releasing its armature removes ground from the sleeve wire 325. The removal of this ground releases relay D-3 whereupon the release magnet 340 operates as follows: free pole of battery, magnet 340, off normal switch contact 341, lower armatures and back contacts of relays B-3 and A-3 to ground at the armature 311 and back contact of relay D-3. Thus the first selector is restored and upon reaching its normal position opens the off normal springs 313 and 341. The removal of ground from conductor 503, by the retraction of right hand armature of relay B-5 releases relay D-5 and the retraction of the right hand armature of relay A-5 and inner left armature of relay B-5 closes a circuit of the release magnet 552 at the toll transmission selector as follows: free pole of battery, magnet 552, lower contact of off normal switch 515, conductor 553, back contact and inner left hand armature of relay B-5 to ground at the right hand armature and back contact of relay A-5.

The slow relay F-5 is energized in parallel with the release magnet and opens the circuit for the test brush 526 during restoration at its lowermost armature. At its armature 554 it short circuits the left hand winding of relay A-5. At its upper armature it closes a locking circuit for itself which is opened when the off normal switch assumes its normal position. The opening of the circuit of the tip and ring conductors 610 and 646 causes the release of relays A-6, B-6, J-6, Fig. 6, which results in the closure of the circuit of release magnet 686: free pole of battery, magnet 686, left hand contact of off normal switch 620, back contact and lowermost armature of relay D-6, lower armature and back contact of relay B-6 and A-6 to ground. The connector upon reaching normal position restores the off normal switch 620.

Referring now to Fig. 7, this represents a combination toll and local connector for party line working. The arrangement for party line working shown employs what is known as segregated grouping, each connector having a generator of a certain char-

acter associated with it and only the stations on the line having bells responsive to this generator appear in the multiple bank of this connector, in accordance with the well known practice. The only difference between the circuits of Figs. 6 and 7 is that a so-called pick-up relay Z-7 is provided to insure that the ringing will commence at the beginning of the code. It will be remembered that if the line is idle relay H-7 operates, and in operating operates relay K-7 which causes the reversal of the current flow in the circuit leading back to the toll operator's position to light the lamp 100 as a ringing signal to her. She thereupon presses the ringing key whereupon relay C-4, Fig. 4, operates to energize relay E-4, Fig. 4, which in operating causes the release of relay F-7. However, when this circuit releases, the relay F-7 does not alone impress ringing current on the called line but instead prepares a circuit for a pick-up relay Z-7 as follows: free pole of battery, relay Z-7, uppermost armature and back contact of relay F-7, normal contact of relay Z-7, conductor 701, armature 702 and front contact of relay H-7, interrupter 700 to ground if the interrupter brushes are on the metallic segment. Thus the relay Z-7 can only be operated before the beginning of the code ringing transmitted by the ringing machine and locks itself over its upper armature to the grounded sleeve wire 714. In attracting its lower armature relay Z-7 prepares the ringing circuit and upon the ringing machine reaching its ringing position code ringing current is impressed on the called line over the following circuit: ringing machine 703, upper winding of relay F-7, lower armature and front contact of relay Z-7, armature 714 and back contact of relay F-7, armature 705, brush 706, multiple 707, through the bell at the called station returning over the upper talking conductor, multiple 708, brush 709, front contact and armature 710 of relay H-7, armature 711, and back contact of relay F-7 to grounded battery pole of the generator. This code ringing continues until the called party answers whereupon the ringing cut off relay F-7 operates connecting the calling and called ends of the talking conductors together and locking itself to the control conductor 712. From this point the operations are the same as those described in connection with Fig. 6.

Referring now to Fig. 9. This figure represents a toll connector circuit, that is to say connectors which are accessible only to the toll transmission selectors of Fig. 5 and not to local selectors. These switches are provided where certain lines have an unusually large amount of toll traffic. When the toll transmission selector of Fig. 5 seizes a connector of Fig. 9, the ground on sleeve

conductor 542 is transmitted over conductor 911, armature 900 and back contact of relay D-9 to the control conductor 901, conductor 541, armature 537 and front contact of relay D-5, control conductor 507 to hold the relay D-4, Fig. 4, energized. When the toll connector is selected by the toll transmission selector, relay A-9 is energized over the loop leading back to the circuit of Fig. 4 as described and the interruption of this loop due to the operation of the dial causes the relay A-9 to transmit impulses over the following circuit to the vertical magnet 902 of the connector: ground, armature 903 and back contact of relay D-9, right hand armature and back contact of relay A-9, conductor 919, outer left armature and front contact of relay F-9, contact 904 of off normal switch 905, slow relay C-9, vertical magnet 902, to free pole of battery. Relay F-9 energizes over its right winding and the right hand armature of relay A-9 when relay A-9 becomes energized. Relay F-9 locks to lead 901. The vertical magnet 902 responding to these impulses at the first step opens off normal switch 905 but relay C-9 remains operated over contact 906 at its armature and front contact. Relay C-9 is slow to release and holds itself energized between the impulses but restores at the end of the first series of impulses and shifts the impulse circuit to the rotary magnet. The impulses corresponding to the units digit now pass over the back contact of the relay C-9. Relay E-9 in the rotary stepping circuit, being slow to release, holds up between the impulses and the second and succeeding impulses pass through the rotary magnet 959, over the lower armature and front contact of relay E-9. Relay E-9 in operating connects the relay B-9 to the test brush 907. If the line is idle however relay B-9 is not operated since there is no ground on the multiple 908 thereof, but full potential through the cut off winding of the called line switch. This current is transmitted over the armature 909 and back contact of relay E-9, inner left armature and back contact of relay B-9, conductor 912, conductor 913, upper winding of relay D-9 to the grounded sleeve wire 911. Relay D-9 gets sufficient current through the bridge cut off winding to operate sufficiently to make its contact Y when its lower winding is brought into circuit which permits it to energize sufficiently to attract all its armatures. In attracting its armatures it disconnects the grounded sleeve conductor 911 from the control conductor 901 to deenergize relay D-4, Fig. 4, which causes the current to be reversed in the trunk leading back to the toll operator's position to cause the lamp 100 to be lighted as a ringing signal as described in detail. In attracting armatures 914 and 915 it connects the incoming and outgoing tip and

ring conductors together and disconnects the relay A-9, the armature 915, however, closing a circuit through resistance 916 to hold the relay A-9 energized. While the attraction of the armature 900 of the relay D-9 removed ground from the holding winding of the relay F-9, ground is returned over the control conductor 901 to the holding winding to hold the same energized and prevent ringing until the operator depresses her ringing key. When she presses her ringing key she operates relay C-4, Fig. 4, which in turn operates relay E-4, Fig. 4, to remove this ground from the control lead. Relay F-9 thereupon releases and transfers the called line from the trunk to the machine ringing circuit. The ringing circuit is as follows: ground at generator 940, left winding of relay F-9, left armature and front contact of relay A-9, outer right armature and back contact of relay F-9, lower talking conductor, through the substation, upper talking conductor, inner left armature and back contact of relay F-9 to grounded battery at the armature and back contact of release magnet 918. When the called party removes his receiver in response to this signal, relay F-9 operates and again locks itself to the control conductor 901 which is now grounded at the right armature and back contact of relay E-4, Fig. 4. In operating it cuts off the ringing current and again extends the called line to the toll trunk. Battery current is fed to the called line over relay A-4 and the repeating coil 406 as in Figs. 4 to 6, and the called subscriber controls supervisory lamp 100 at the switch hook contacts.

When the connection is broken down relays D-9 and F-9 release. Relay D-9 releases relay A-9 and the circuit of the release magnet 918 is closed as follows: free pole of battery, magnet 918, upper make contacts of off normal switch 905, outer left armature and back contact of relay F-9, conductor 919, right armature and back contact of relay A-9 to ground at the armature 903 of relay D-9. When the switch reaches its normal position the off normal switch 905 is restored to normal.

If the selected line is busy slow relay B-9 is operated from ground at the multiple 908, test brush 907, armature 909 and front contact of relay E-9, slow relay B-9 to free pole of battery. Relay B-9 then locks itself over make before break contact 910 at its inner right armature and front contact to the grounded sleeve wire 911. Thus no circuit is closed through the upper winding of the relay D-9 to operate the same to release the relay D-4, Fig. 4, to reverse the direction of current flow in the circuit leading back to the operator's position. Consequently relay G-2, Fig. 2, is not operated and the interrupter 233 is connected in shunt of the resistance 200 to intermittently operate relay B-43 in the operator's cord circuit when she restores her dialing key DK. Thus, the supervisory lamp is flashed to indicate that the line is busy as particularly described in connection with Fig. 6.

Referring now to Fig. 8, this figure shows a toll rotary connector, that is to say a switch which is only reached from the toll transmission selectors and in which each subscriber may have a number of lines running to his station. When this connector is seized by the toll transmission selector, impulse relay A-8 operates over the loop and operates slow relay B-8. Tens impulses pass from ground at the armature 800 and back contact of relay B-8, armature and back contact of impulse relay A-8, left armature and front contact of relay B-8, contact 801 of off normal switch 802, magnet 803, slow relay C-8 to free pole of battery. Thus, the connector is lifted to the desired level. Upon the termination of the tens impulses, the relay C-8 releases. The units impulses pass from ground at the armature 800 and back contact of relay D-8 armature and back contact of relay A-8 left hand armature and front contact of relay B-8, contact 804 of the off normal switch 802, armature 805 and back contact of slow relay C-8, conductor 806, conductor 807, armature 808 and back contact of relay K-8, conductor 809, slow relay E-8, conductors 810 and 811, armature 812, and back contact of relay H-8, conductor 813, rotary magnet 814 to free pole of battery. Magnet 814 rotates the connector into engagement with the first P. B. X. trunk. Slow relay E-8 remains energized while the impulses are being transmitted. If the first P. B. X. trunk is busy test multiples 815 and 816 will be grounded. The ground on multiple 816 is transmitted over test brush 817, conductors 818 and 840, armature 819, and front contact of slow E-8, conductor 820, armature 821, and back contact of relay H-8, conductor 822 and relay K-8 to free pole of battery. Relay K-8 energizes and locks itself in the following circuit: free pole of battery, relay K-8, conductor 822, armature 821, and back contact of relay H-8, conductor 820, contact 824 of relay E-8, armature 825 and front contact of relay K-8, contact 826 of relay C-8 to grounded sleeve wire 837. Relay K-8 in operating closes the following circuit for relays C-8 and G-8: free pole of battery, relays C-8 and G-8 armature 827 and front contact of relay K-8 armature and back contact of rotary magnet 814, conductor 828, armature 830, and back contact of relay E-8, conductor 831, test brush 832 to grounded multiple 815. Relay C-8 in attracting armature 833 disconnects re-

lay K—8 from the grounded sleeve wire and connects said relay K—8 over conductors 834 and 818 to grounded multiple 816. Relay G—8 closes the following circuit for the rotary magnet 814 to rotate the connector on to the next trunk: free pole of battery, rotary magnet 814, conductor 860, conductor 813, armature 812 and back contact of relay H—8, conductor 811, lower armature and front contact of relay G—8, conductor 836 to grounded sleeve wire 837. Rotary magnet 814 at the end of its stroke breaks the circuit of relays G—8 and C—8. Relay G—8 in retracting its lower armature opens the circuit of the rotary magnet. Relay C—8 opens the energizing circuit of relay K—8, which released when brush 817 reaches the idle trunk. Assuming that this trunk is idle, potential on the test terminal 838 thereof through the bridge cutoff winding of the line is transmitted by brush 817 conductor 818, conductor 840, armature 819 and back contact of relay E—8, conductor 841, the upper winding of relay H—8, conductor 842, upper outer armature and back contact of relay K—8, conductor 843, outer armature and front contact of relay B—8 to ground. Relay H—8 in attracting its armature 845 locks itself to grounded sleeve wire 837 and extends this ground over conductor 847 to relay D—8 which in operating cuts off impulse relay A—8 and disconnects grounded sleeve conductor 837 from the control conductor 848, at its armature 849. Thus, the deenergization of relay D—4, Fig. 4, follows, which causes the current to be reversed in the trunk leading back to the toll operator's position, which results in the lighting of the lamp 100 as a ringing signal to the operator. Relay F—8 was operated upon the operation of relay B—8 when the toll transmission selector seized the connector. The operation of relay D—8 in attracting its armature 850 opens the original circuit for the relay F—8 but before this relay which is slow can be deenergized a substitute circuit is closed over control conductor 848 as described. The armature 854 of relay H—8 applies a direct ground over conductor 818 to the test multiple 838 of the seized line and this ground is transmitted by the conductor 855 to the test multiple 856. Thus this trunk will test busy to other connectors. When the operator depresses her ringing key it operates alternating current relay C—4 to energize relay E—4 which removes ground from the control lead and consequently relay F—8 releases connecting at its armature 851 and 852 the ringing machine in circuit with the called line to signal the subscriber. Upon the response of the subscriber relay F—8 operates by means of its lower winding and again locks up to grounded control wire 848. Current is fed to the called line over the

relay A—4 and the repeating coil 406, Fig. 4. Each of the P. B. X. trunks may have a coin box connected therewith. The operator now asks the party to deposit the necessary coins and the operation of collecting the coins is the same as that described in connection with Figs. 1 to 6, the coin current being transmitted over the tip and ring conductors 857, 860, to operate the polarized magnet in the coin box to collect or refund the coins as the case may be.

The called subscriber by operating his switch hook flashes the supervisory lamp 100 at the toll operator's position. After the called subscriber replaces his receiver, the operator can, by actuating her ringing key RK, again cause the connector to start the ringing operation until the called party answers. When the called subscriber replaces his receiver relay A—4 releases, de-energizing relay B—4 which again connects current to the trunk leading back to the operator's position to operate relay B—43 to light the supervisory lamp 100 permanently as a disconnect signal. The operator thereupon removes the plug which results in the release of the switches as described. The release circuit of the P. B. X. connector is as follows:—battery, release magnet 853, lower make contact of off normal switch 802, left armature and back contact of relay B—8, lower armature and back contact of relay A—8, armature 800 and back contact of relay D—8 to ground. The off normal switch is restored when the connector shaft reaches its normal position.

The relay H—4 is provided to permit the toll operator to manually apply ringing current to the selected private branch exchange line to signal the operator thereat. This relay is operated when relay E—4 is operated due to the actuation of the ringing key by the toll operator. The circuit for operating relay H—4 extends from grounded battery from the winding of relay H—4, left-hand contacts of relay E—4 to ground at the contacts of relay A—4. Relay H—4 is not operated when reringing on the line other than a private branch exchange line because in such a case, there is no bridge across the T and R conductors to energize relay A—4. If relay A—4 is not operated, relay H—4 cannot be operated when relay C—4 is energized because the ground at the contacts of relay A—4 is not in circuit with the winding of relay H—4. In private branch exchange working the called subscriber may hang up his receiver, but due to the bridge at the P. B. X. operator's board the relay A—4 remains operated and thus no signal is given to the toll operator. Circuits for private branch exchanges where a bridge is placed across the operator's cord circuit, when the subscriber at the private branch exchange hangs up his receiver, are old and

well known in the art, for example, as shown in Patent 1,232,507 of July 10, 1917 to H. L. Darrah.

What is claimed is:

5. 1. In a telephone system, the combination with telephone lines, a connection comprising a connecting circuit, a pair of said lines and automatic switches, a coin box at the substation of one of said lines having a coin disposal magnet, an operator's position, an automatic switch at said position and controlled therefrom to connect with said connecting circuit, and means associated with said automatic switch and operative upon 10 selection of said connecting circuit for operating said magnet.
2. In a telephone system, the combination with telephone lines, a connection comprising a connecting circuit, a pair of said lines and automatic switches, a coin box at the substation of one of said lines having a coin disposal magnet, an operator's position, an automatic switch at said position and controlled therefrom to connect with said connecting circuit, a pair of paths to said automatic switch over either of which it may be set, and means for selectively operating said magnet determined by the path chosen.
3. In a telephone system, the combination with telephone lines, a connection comprising a connecting circuit, a pair of said lines and automatic switches, a coin box at the substation of one of said lines having a coin disposal magnet, an operator's position, an automatic switch at said position and controlled therefrom to connect with said connecting circuit, a source of refund and a source of collect current, and a pair of paths to said automatic switch over either of which it may be set, one of said sources being associated with each path to correspondingly operate said magnet when the connecting circuit is selected.
4. In a telephone system, the combination with telephone lines, a connection comprising a connecting circuit, a pair of said lines and automatic switches, a coin box at the substation of one of said lines having a coin disposal magnet, an operator's position and an automatic switch at said position and controlled therefrom to connect with said connecting circuit, a pair of jacks in which the circuit leading to said automatic switch terminates, a source of refund current associated with one jack and a source of collect current associated with the other, a dial and a plug adapted when inserted in either jack to associate said dial with said switch to set the same on said connecting circuit, and means operative when the same is selected to impress current from the corresponding source to cause said magnet to collect or refund the coins.
5. In a telephone system, the combination of telephone lines, a connection comprising 65 a connecting circuit, a pair of said lines and automatic switches, a coin box at the substation of one of said lines having a coin disposal magnet, an operator's position, a head set thereat, an automatic switch at said position and controlled therefrom to select said connecting circuit, a pair of paths to said automatic switch over either of which it may be set, a source of refund and a source of collect current, one of said sources being 70 associated with each path to correspondingly operate said magnet when the connecting circuit is selected, and two sources of tone current the corresponding one of which is connected in circuit with said head set when current is applied to the line to operate said magnet.
6. In a telephone system, the combination of telephone lines, a connection comprising 75 a connecting circuit, a pair of said lines and automatic switches, a coin box at the substation of one of said lines having a coin disposal magnet, an operator's position, a head set thereat, an automatic switch at said position and controlled therefrom to select 80 said connecting circuit, a pair of paths to said automatic switches over either of which it may be set, a source of refund and a source of collect current, one of said sources being 85 associated with each path to correspondingly operate said magnet when the connecting circuit is selected, two sources of tone current the corresponding one of which is connected in circuit with the head set of the operator when said current is applied to the line to 90 operate said magnet, and means operated by the magnet in disposing of said coins for removing said tone.
7. In a telephone system, the combination of telephone lines, a connection comprising 95 a connecting circuit, a pair of said lines and automatic switches, a coin box at the substation of one of said lines having a coin disposal magnet, an operator's position, a head set thereat, a pair of jacks in which the circuit leading to said automatic switch terminates, a source of refund current associated with one jack and a source of collect current associated with the other, a dial and a plug adapted when inserted in either jack to associate said dial with said switch to set the same on said connecting circuit, means operative when the connecting circuit is selected to impress current from the corresponding source to cause said magnet to collect or refund the coins, a ground connection at the substation for maintaining said source connected to the line, two sources of tone current, the corresponding one of which is connected to the operator's head set while current is applied to the line, said magnet operating to dispose of the coins removing 100 said ground path whereby said tone source is

disconnected from said head set, and means actuated upon the removal of the plug for restoring said automatic switch.

8. In a telephone system, telephone lines, a connection comprising a connecting circuit, a pair of said lines and automatic switches, a coin box at the substation of one of said lines having a polarized coin disposal magnet, a toll operator's position, an automatic switch in said position, a pair of manual switches over either of which said dial may be associated with said automatic switch to set same on said connecting circuit, a source of positive current associated with one switch and a source of negative current associated with the other, and means operative upon the selection of said connecting circuit for connecting the corresponding source of current to operate said coin disposal magnet.
10. 9. In a telephone system, telephone lines, a connection comprising a connecting circuit, a pair of said lines and automatic switches, a

coin box at the substation of one of said lines having a polarized coin disposal magnet, a toll operator's position, an automatic switch 25 in said position, a pair of manual switches over either of which said dial may be associated with said automatic switch to set the same on said connecting circuit, a source of positive current associated with one 30 switch and a source of negative current with the other, means operative upon the selection of said connecting circuit for connecting the corresponding source of current to operate said coin disposal magnet, two sources of 35 tone current, one associated with each manual switch, and means for connecting the corresponding tone to the operator's head set while current is impressed upon the line to operate said magnet. 40

In witness whereof, I hereunto subscribe my name this 23rd day of September A. D., 1920.

RAY L. STOKELY.
